ROTATING ALBUM MIRROR

Sanford B. Megdall, Brooklyn, N. Y.

Application November 8, 1932, Serial No. 641,695
Renewed April 27, 1935

4 Claims. (Cl. 40—70)

This invention relates to a rotating album mirror.

The object of the invention is the production of a rotating album mirror, by means of which a plurality of pictures or legends can be brought in view one after the other.

The second object of the invention is the production of a rotating album mirror, in which a plurality of sector shaped tablets with pictures or legends can be detachably inserted, and brought into view through an opening in the backing of the mirror of the device.

In the accompanying drawing Fig. 1 represents a front view, partly broken away, of an exemplification of the improved rotating album mirror; Fig. 2 shows a rear view of Fig. 1; Fig. 3 indicates a front view of the supporting plate of the album mirror, before being folded in place and with its appurtenances; Fig. 4 represents an enlarged section of Fig. 1 on the line 4, 4; Fig. 5 shows an enlarged fragmentary portion of the rotatable supporting disc of the device with a sector shaped picture tablet; Fig. 6 is a section of Fig. 5 on the line 6, 6, and Fig. 7 shows a top view of the rotatable supporting disc.

The supporting plate is shown with the body portion 20, having the side walls 21, the top wall 23 and the bottom wall 24 at right angles to said body portion. Flanges 26 extend at right angles from the side walls 21. A flange 27 extends at right angles from the top wall 23 and a flange 28 extends at right angles from the bottom wall 24. Hood shaped spacer heads 32 are pressed out from the body portion 20. The dotted lines 35, 36 and 37, 38 indicate the creases formed in the blank for the body portion 20 to form the side walls 21, the flanges 26, the top wall 23 with its flange 27 and the bottom wall 24 with its flange 28. From the body portion 20 are pressed the U shaped flanges 40 to form the journal bearing seats 41. The openings 42 result in the body portion of the supporting plate 20, by pressing out the flanges 40. An opening 45 is indicated in the top end 45 of the body portion 20.

Upon the body portion 20 is supported the rotating supporting disc 50, having the circumferential corrugated edge 51, the circular axial opening 52, and a plurality of small radial elongated openings 53. A plurality of radially positioned supporting plates 55 are forwardly pressed out of the disc 50 leaving the openings 56. At the ends of each plate 55 are indicated the pair of stop legs 57 which space and connect each supporting plate 55 and the supporting disc 50.

A mirror is indicated with its glass 60 having its usual mercury backing 61. A heart shaped opening 62, in this instance, is indicated in the mercury backing 61.

An outer case for the album mirror, which may be of celluloid or other material, is indicated with the body portion 65 having the opening 66 opposite the opening 45. A top wall 68 with the front flange 69, and the bottom wall 70 with the front flange 71 are shown integral with the body portion 65. The body portion 65 bears against the body portion 20 of the supporting plate, the wall 68 bears against the wall 23 and the flange 69 bears against the flange 27. The wall 70 bears against the wall 24 and the flange 71 bears against the flange 28. Side flanges 75 of the body portion 65 bear against the flanges 26.

The mirror 60 bears between the heads 32 and the flanges 26, 27 and 28.

The top faces of the supporting plates 55 clear the outer face of the mercury backing 61.

A sector shaped tablet 80 having the radial edges 81 and the photograph 82 or other picture or legend can be detachably supported between each pair of supporting plates 55, the edges 81 bearing against the side faces of the stop legs 57. It will be noted that a different picture or legend is indicated on each of the tablets 80.

To use the rotating album mirror the tablets 80 are inserted through the openings 45 and 66, and positioned between the supporting plates 55 with their edges 81 bearing against the stop legs 57. The disc 50 is turned by bearing on its corrugated edge 51, to locate the pictures on the tablets 80, one after the other opposite the opening 62.

The tablets 80 can be removed from the disc 50 when they are opposite the openings 45 and 66, by inserting a pin through the openings 53, when they are opposite the openings 45 and 66 and engage said tablets 80 to move them outwardly from the disc 50.

Attention is called to the fact that the opening 62 can be of various shapes.

Various modifications may be made in the invention and the present exemplification is to be taken as illustrative and not limitative thereof.

Having described my invention, I claim.

1. In an album mirror the combination of a mirror glass having a portion of the mercury backing removed to form an opening, a rotating supporting disc journaled to the rear of said mirror glass and, a plurality of supporting plates extending from said supporting disc, adapted to

support a tablet having a picture between each pair of supporting plates, said rotating supporting disc having openings between its supporting plates for the insertion of an element to detach the 5 tablets having the pictures thereon from said supporting disc.

2. In an album mirror the combination of a mirror glass having an opening in its mercury backing, a supporting plate to the rear of the 10 mirror glass and with its body portion spaced therefrom, a rotating supporting disc journaled to the supporting plate and positioned between it and the rear face of the mirror glass, diametrically positioned supporting plates extending from 15 said disc positioned between it and the rear face of the mirror, a pair of stop legs at the ends of each supporting plate connecting it to said disc, a sector shaped tablet adapted to be secured in place between each pair of supporting plates with 20 its diagonal edges bearing against the pairs of said stop legs and a different picture on each of said tablets, the said pictures brought in view when opposite the opening in the mercury backing.

25 3. In an album mirror the combination of a mirror glass having an opening in its mercury backing, a supporting plate to the rear of the mirror glass, hood shaped spacer heads extending from the supporting plate bearing against 30 the mercury backing, to space the supporting plate to the rear of the mirror glass, said supporting plate having an opening at the top end there-

of, a rotatable disc journaled to the supporting plate and positioned between it and the mirror glass, diametrically positioned supporting plates extending from said disc toward said mirror glass, a stop leg at each end of each supporting plate connecting said plate and said disc, a sector shaped tablet positioned between each pair of supporting plates, bearing on said rotatable disc with its radial edges extending under a portion of each supporting plate and bearing against the 10 stop legs thereof, and an outer backing having an opening for the mirror. 5

4. In an album mirror the combination of a mirror glass having an opening in its mercury backing, a supporting plate to the rear of the 15 mirror glass, means integral with said supporting plate to space it from the mirror glass, a rotatable supporting disc journaled to the supporting plate between it and the mirror glass, a plurality of radially disposed stop legs extending up from said 20 rotatable disc toward said mirror glass, radially disposed supporting plates in planes above said stop legs and co-acting therewith and spaced from said rotatable supporting disc and tablets having legends thereon detachably secured between accompanying stop legs and below their 25 supporting plates, the rotatable supporting disc adapted to be positioned to locate the tablets thereon opposite the opening in said mercury backing. 30
